UNITED STATES PATENT OFFICE.

IRA BAILEY WALKER, OF ETNA MILLS, CALIFORNIA.

SIGNALING DEVICE.

1,375,806.

Specification of Letters Patent. Patented Apr. 26, 1921.

Application filed March 31, 1920, Serial No. 370,275. Renewed March 12, 1921. Serial No. 451,842.

To all whom it may concern:

Be it known that I, IRA BAILEY WALKER, a citizen of the United States, and a resident of Etna Mills, in the county of Siskiyou and State of California, have invented certain new and useful Improvements in Signaling Devices, of which the following is a specification.

My invention is an improvement in signaling devices, and has for its object to provide mechanism of the character specified adapted to be arranged on highways for warning drivers approaching each other from opposite directions, at dangerous places in the road, wherein each car, as it approaches the danger point, operates mechanism which controls a signal at the opposite side of the danger point, means being provided in connection with the signal for causing it to be displayed a specified length of time and to afterward permit it to move into inoperative or non-display position, and wherein the means operated by the vehicle is so arranged that only vehicles moving in one direction will operate the same.

In the drawings:

Figure 1 is a front view of the improved signal;

Fig. 2 is an enlarged vertical section through a portion of the roadway showing the operating means for the signal controlled by the vehicle;

Fig. 3 is a sectional view showing the means for causing the signal to be displayed a predetermined length of time;

Fig. 4 is a perspective view of one of the bell cranks;

Fig. 5 is a perspective view of the weight-controlled plate;

Fig. 6 is a perspective view of the guide for the plate;

Fig. 7 is a diagrammatic view showing the arrangement for a crossing.

In the present embodiment of the invention suitable posts 1 are arranged at the opposite sides of a danger point, as, for instance, a narrow place or turn, or, as shown in Fig. 7, the posts may be arranged on the four sides of a crossing or road intersection. Each post is provided near its top with a semaphore arm 2 which is pivoted to the post, as indicated at 3, and each semaphore arm carries a legend, as, for instance, "Car coming", or any other desired warning.

The pivot pin 3 upon which the arm

swings is fixed, and the semaphore arm 2 has an extension 4 which has a bearing engaging the pin. The semaphore arm is moved into the dotted line position of Fig. 60 1 from the full line position of the said figure by the mechanism shown in Fig. 2. At a suitable distance on each side of the danger point or from the intersection of the two roads, there is provided a pit 5 at one side 65 of the roadway and in position such that one side of a vehicle must pass over the pit, the pit being of a length sufficient to insure that the car cannot pass without passing over the pit.

Referring to Fig. 2, it will be seen that one wall of this pit, namely, that wall remote from the danger point, is perpendicular, as indicated at 6, while the opposite wall 7 is undercut. Within this pit there is arranged a block or plate 8 which normally abuts the perpendicular wall 6 and which is normally held elevated so that a portion thereof extends outside of the pit and above the roadway by means of plate springs 9 80 which are suitably mounted in the pit. That portion of the bottom of the pit just below the block 8 is so spaced from the top of the roadway that when the block is in engagement with the said bottom portion the 85 upper edge of the block will be flush with the surface of the roadway.

The pit is of greater width than the block, being of such width that when a vehicle coming from the left of Fig. 2 strikes the 90 block the plate 8 or said block may swing with the moving vehicle a sufficient distance to operate the semaphore arm 2 before engaging the upper edge of the beveled wall 7.

A coil spring 10 is arranged between the 95 block and a fixed point in the roadway, and this spring acts normally to hold the block in the position shown in Fig. 2. That portion of the pit bottom which is not below the block or plate 8 is deepened, as shown 100 at 11, to receive foreign bodies that might fall into the pit and to provide a receptacle for such bodies so that they will not interfere with the proper working of the block 8.

A link 12 is connected with the block or 105 plate 8 at one end and at the other with a bell crank 13 which is pivoted at a suitable point in a conduit or tunnel 14 which leads from the pit 5 to the post 1 with which the block 8 is designed to be connected. An 110 other bell crank 15 is arranged at the bottom of the post and the bell cranks 13 and 15

are connected by connections 16, which may be wires or the like. From the bell crank 15 a flexible member 17 passes upwardly over direction elements 18 at the top of the 5 post and then downwardly to a connection with the extension 4 of the semaphore arm. The arrangement is such that when the block or plate 8 is swung toward the undercut wall 7 of the pit the flexible member 10 17 will be moved in a direction to swing the semaphore arm into the broken line position of Fig. 1.

In order to prevent the block or plate 8 from operating the semaphore arm when 15 moved by the kick-back of vehicles moving away from the signal, a latch 19 is secured to the block, and this latch is designed to engage a catch 20 fixed in the roadway on the pit wall 7. When the block 20 or plate is pressed directly downward by a vehicle coming from the right of Fig. 2 the latch 19 will engage the catch 20 so that the kick-back of the vehicle wheels will not tend to swing the plate or block away 25 from the wall 6. As soon as the springs 9 move the plate or block upwardly the latch will release the catch.

Means is provided for insuring that the 30 semaphore arm will be displayed a predetermined time and then released to permit it to move into operative position by its own weight. The said means is in the form of a lever 21 which is pivoted to the post adjacent to the semaphore arm. This lever is 35 adapted to be engaged by a ratchet bar 22 rigid with the bearing of the extension 4. When the signal is moved upwardly into the broken line position of Fig. 1 the ratchet bar engages one end of the lever 21, and 40 swings the said lever. The other end of the lever extends into a casing 23 which is secured to the post adjacent to the semaphore arm and is adapted to engage a mechanism to be later described.

45 A plate 24 is mounted to move vertically on a pin 25 on a block 26 which is secured within the case. The plate has an opening through which the pin extends, and the said plate rests upon one end of a lever 27 which 50 is pivoted at 28 in the casing. The other end of the lever engages the body of the fork or yoke 29 at the upper end of a pendulum assembly 30, which is pivoted at 31 in the casing.

55 This pendulum assembly is a part of an escapement mechanism, comprising, in addition, a toothed wheel 32 journaled in the casing, and the arms of the fork or yoke engage the teeth of the wheel in such manner 60 that when the pendulum swings the wheel will be permitted to rotate in the manner of an escapement.

A lever 33 is pivoted to the axis of the wheel, and this lever carries a weight 34 65 at the end adjacent to the plate 24 and

which is adapted to engage the said plate 24 under conditions to be presently described.

A pawl 35 is pivoted to the lever, and this pawl 35 is pressed into engagement with the teeth of the wheel 32 by a spring 36 arranged between the pawl and the lever.

The operation of this part of the mechanism is as follows:

When the semaphore arm is swung upwardly the lever 21 is rocked, and that end of the lever which is within the case engages the weight 34 and lifts said weight, as shown in Fig. 3. The pawl by its engagement with the ratchet wheel 32 prevents downward movement of the weight, unless the wheel turns as the weight moves down, and the escapement mechanism slows the movement of the wheel 32. It will be obvious that by proper arrangement of the parts, the extent of time required for the downward movement of the weight to be completed may be of any length desired.

The semaphore arm must be displayed until the approaching vehicle has rounded 90 the turn or passed the corner. After the weight has descended a predetermined distance it engages the plate 24, and this plate is moved downwardly, swinging the lever 27, which swings the pendulum, the inner 95 end of the lever being in engagement with the body of the yoke and stops the movement of the pendulum, with one of the arms of the yoke in engagement with the teeth of the wheel, thus checking the movement of 100 the wheel, as indicated in dotted lines in Fig. 3. A gong 35 is arranged within the casing in such position that when the pendulum swings it will strike the gong to provide an audible warning.

At a crossing, for instance, one of the 105 posts 1 provided with its signal is arranged on each side of the crossing on each roadway, as shown in Fig. 7, and a pit 5 provided with its block 8 is arranged in suitable position near each post. Each of the blocks 8 is connected with the semaphore arms of the posts on the roadway at right angles to the roadway in which is the pit, so that when the block 8 is swung by a vehicle approaching the crossing signals will 110 be displayed on the cross road at each side of the crossing.

Where there is a bad turn or any other danger point on a single road, signals will 115 be arranged on each side thereof and so connected that a vehicle approaching from either direction will display the signal on the opposite side of the danger point.

I claim:

1. In combination with a semaphore arm and means adapted to be controlled by a moving car for lifting said arm to danger position, means for holding said arm in danger position independent of the vehicle 130

controlled operating means, and time controlled means for releasing said holding means after a predetermined length of time, and an audible signal operated by the time controlled means.

5. 2. In combination with a semaphore arm and means adapted to be controlled by a moving car for lifting said arm to danger position, means for holding said arm in 10 danger position independent of the vehicle controlled operating means, and time controlled means for releasing said holding means after a predetermined length of time.

15. 3. In combination with a normally inoperative signal and means controlled by a moving vehicle for operating said signal to danger position from a distance, means independent of the vehicle controlled means for holding said signal in danger position, 20 and means for releasing said holding means after a predetermined length of time to permit the signal to move into inoperative position.

25. 4. In combination with a normally inoperative signal and means controlled by a moving vehicle for operating said signal to danger position from a distance, and means independent of the vehicle controlled means for holding said signal in danger position for a predetermined length of time 30 after the passage of the vehicle.

35. 5. In combination, a semaphore arm supported to normally swing into inoperative position, vehicle controlled means operable from a distance for lifting said arm to dan-

ger position, releasable means for holding the arm lifted and escapement-controlled means for releasing said holding means after a predetermined length of time.

6. In a device of the character specified, 40 the combination with the semaphore arm, of means controlled by a moving vehicle for operating the same, said means including a block adapted to be engaged by the wheels of the vehicle, said block having guided 45 movement to be moved laterally and then vertically when engaged by the wheels of a car going in one direction and to be moved vertically when engaged by the wheels of a car going in the other direction, springs 50 for holding the block in normal position in the path of movement of the wheels, and means for preventing lateral movement in the first named direction under the kick-back of the vehicle wheels. 55

7. In a device of the character specified, the combination with the semaphore arm, of means controlled by a moving vehicle for operating the same, said means including a block adapted to be engaged by the wheels 60 of the vehicle, said block having guided movement to be moved laterally and then vertically when engaged by the wheels of a car going in one direction and to be moved vertically when engaged by the 65 wheels of a car going in the other direction, and springs for holding the block in normal position in the path of movement of the wheels.

IRA BAILEY WALKER.
